(57) **CLAIM**

The ornamental design for an ultrasound flow meter as shown and described.

DESCRIPTION

FIG. 1 is a perspective view of an ultrasound flow meter showing our new design;

FIG. 2 is an end view of the ultrasound flow meter of FIG. 1;

FIG. 3 is a side elevation view of the ultrasound flow meter of FIG. 1;

FIG. 4 is an alternate end view of the ultrasound flow meter of FIG. 1;

FIG. 5 is an alternate side elevation view of the ultrasound flow meter of FIG. 1;

FIG. 6 is a top plan view of the ultrasound flow meter of FIG. 1; and,

FIG. 7 is a bottom plan view of the ultrasound flow meter of FIG. 1.
